ATTORNEYS.

Patented July 26, 1927.

1,636,723

UNITED STATES PATENT OFFICE.

ERNEST UNGER, OF NEW YORK, N. Y.

CHANDELIER.

Application filed October 28, 1924. Serial No. 746,264.

The invention relates in general to an overhead bracket or chandelier for supplying electric current to a plurality of outlets and especially relates to such a chandelier for supplying current to a plurality of hair waving heating units for use in waving or otherwise treating the hair on a person's head. The invention constitutes a development of the invention disclosed in my patent 10 on chandelier No. 1,406,508, February 14, 1922.

The invention herein disclosed has the same general objects as was mentioned in the above identified patent in that they are 15 designed to meet trade conditions which require maximum number of outlets confined within a limited space, accessibility to the several outlets without interference from the flexible connections leading to the heaters and above all to provide a form of bracket which can be manufactured at minimum cost.

In the above identified patent there was featured a depending support having a foot 25 bracket at its lower end and from which extended radially a plurality of socket receivable supporting arms, from each socket of which extended leads for supplying several hair heating devices. The central bracket 30 contained a pair of control switches each controlling all of the sockets in a pair of the carrying arms and each switch also controlled a pilot light for indicating the activity of each of the gangs of these sockets.

The present disclosure has for a general object the providing of the control switches and their associated pilot lights as parts of each of the replaceable arms in distinction from the disposing of the lights and 40 switches in the central foot bracket. In this way the activity of the heaters associated with each particular arm can be readily indicated by the luminosity of the pilot light carried by the associated arm and the replacing of any one arm will replace its associated switch and light.

Other objects of the invention are to provide a construction which will feature a compact disposition of a relatively large 50 number of outlet sockets within a small overall space considered lengthwise of each arm; the utilization of a standard form of double-end socket positioned exteriorly of the supported arm and easily available for 55 repair or substitution of damaged parts and the disposing of the electric leads so that

their connections with both the sockets and the main leads in the support are readily accessible.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings: 70

Figure 1 is a view in side elevation of a preferred embodiment of the invention and showing a pair of heaters supplied from one end of one of the sockets.

Figure 2 is a view partly in side elevation 75 and partly in vertical section of one of the arms shown in Figure 1.

Figure 3 is a plan view looking down upon the structure shown in Figure 2 and with part of the top plate of the arm removed to show the contained electrical connections. 80

Figure 4 is a detail view showing one of the connections between a socket and its associated arm and 85

Figure 5 is a diagrammatic view showing the current carrying elements of one of the arms.

In the drawings and referring first to Figure 1, for a general description of the device, there is shown a depending support 10 formed of square tubing and designed to be secured to the ceiling as is usual in bracket structures. The lower end of the support is fitted into a hollow foot bracket 11 which is of a general rectangular box-like form. A plurality of socket containing arms 12 extend radially from the side of the bracket and provide supports for a plurality of longitudinally spaced apart replaceable units 13 each constituting a double end plug and socket connection for supplying the heaters 14 hereinafter described. The arms 12 are of a hollow, somewhat T shaped form as shown in cross-section Figure 4 with their inner ends enlarged to form fastening plates 15 secured to the adjacent flat sides of the bracket 11 by bolts 16. It is a feature of this disclosure that removing bolts 16 of any one of the arms will permit the separation of the arm from the main part of the chandelier and the removing of the arm will 100 105 110

remove with it all parts of the electric features except the main leads contained in support 10 and foot bracket 11. In other words each arm is a marketable unit complete in itself with all the necessary electric connections to supply and control the heaters which may be plugged into the same.

The arms, except for their removable cover plates 17, are each formed of a one-piece casting 18 open at the top and shouldered as shown at 19 to receive the cover plate. The outer end of the casting beyond the cover plate is enlarged to form a flat shaped housing, 20, for supporting a control switch 21 and for providing a support on its upper side for a pilot light socket 22 carrying a pilot light 23.

The switch 21 is a standard form of four-point switch including a mechanism containing housing 24 intruded into and secured to the underside of the housing 20. The movable contact element 25 of the switch is controlled by a finger-piece 26 depending therefrom as shown in Figures 1 and 2. This disposition of switch at the outer end of the arms and with its control finger-piece depending is designed to provide convenient access to the switch on the part of the operator who reaches upwardly to manipulate the switch.

As a feature of this disclosure that the outlets for the electric current to supply the heaters 14 are positioned close together so as to obtain the greatest possible number of outlets with the least length of arm.

The units 13 are conventional forms of double-end sockets including open end shells 27 into opposite ends of which are demountably screwed plugs 28 and which plugs are connected electrically to the heaters 14 by flexible cables 29. The double-end sockets are positioned exteriorly of their associated arms, and project laterally on opposite sides of the arm as particularly shown in Figure 3. This disposition permits the use of a standard form of socket and disposes the sockets in the closest possible relation considered longitudinally of the arms. In order further to obtain a maximum number of heater supplied from a short length of an arm, the plugs 28 are wired to receive more than one of the cables 29. In one embodiment of the invention it has been found practicable to supply two heaters (as shown in Figure 1) from each plug. This would mean that four heaters can be supplied from a single socket.

For the purpose of mounting the socket units 13 in place the underside of each arm is provided with a plurality of smooth openings 30 which are positioned as close together as the dimensions of the sockets will permit. Loosely positioned in each of the openings is a tubular reduced neck extension or nipple 31 shown in Figure 4. The end of the nipple 31 is inserted into the upstanding

lug 32 which forms part of the socket unit 13. The lug is secured to the projecting end of the nipple and held from turning by a pin 33 and a nut 34 positioned within the arm engages the upper end of the nipple and when tightened secures the parts firmly in place.

In constructing a chandelier it will be understood that main leads 35 are contained in the support 10 and foot bracket 11 with sufficient excessive length at the upper end to provide the necessary electric connection with the house mains. Each arm is provided with its own wiring which includes a pair of main leads 36 and 37 which project out of the open end of the arm and are designed to be connected to the end of the dependent leads 35 in an approved connection indicated symbolically by the soldered connection at 38.

As shown in Figure 5, the main leads are connected respectively to two contact points 39 and 40 of the four-point switch 21. From the corresponding other points 41 and 42 of the switch extend heater leads 43 and 44 which extend lengthwise of the arm to the socket nearest the foot bracket. From the heater leads extend branch leads 45 which extend through the nipples 31 to supply electric current to opposite ends of the sockets 13. From the fixed contact points 41 and 42 of the switch also extend pilot light leads 46 and 47 which supply the pilot light 23.

From the construction disclosed it is apparent that ready accessibility is provided to the several electric leads for the removing of the cover 17 provides access to the main leads 36 and 37; to the heater leads 43 and 44 and to one end of the branch leads 45. The control switch housing 24 may be unscrewed from the enlargement of the casting forming the housing 20 at the outer end of the arm thus providing access to the points of the switch and to the connection of the switch with the electric heaters and pilot light supplying leads.

In operation it will be understood that the parts assembled as herein disclosed, the manipulation of the switch and at the outer end of the arm will control the heaters and the pilot light carried by that particular arm.

The luminosity of the pilot light will indicate positively that the heaters supplied from that arm carrying the pilot light are active. Should any one of the pilot lights go out or fail to light when the switch is manipulated this would indicate to the operator that something was wrong with the connections in that particular arm.

With additional replacement arms any particular defective arm can be readily removed simply by loosening the securing bolts, installing a new unit to take the place of the defective unit and making the necessary electric connections to the main leads.

Similarly one of the sockets may be quickly replaced by loosening the nut securing the nipple to the arm, dropping the old socket from the arm, breaking the electric connections and replacing a new socket.

Having thus described my invention, I claim:

1. A chandelier for supporting a plurality of electric heaters in operative position relative to a person's head in the process of waving the hair on the head, including a depending support, a plurality of horizontally disposed hollow arms extending radially from the lower part of said support; a plurality of replaceable units secured in spaced relation to each of said hollow arms and positioned exteriorly of and below the same, each of said units provided with means constituting sockets for receiving electric attachments from the heaters and electric leads extending down through said support and through said hollow arms into said units.

2. A chandelier for supporting a plurality of electric heaters in operative position relative to a person's head in the process of waving the hair on the head, including a depending support, a plurality of horizontally disposed hollow arms extending radially from the lower part of said support; a plurality of shells constituting double sockets demountably secured to each of said arms and facing laterally in opposite directions and electric leads extending down said support and through said hollow arms to each of the double sockets.

3. A chandelier of the type described including a horizontally extending hollow arm provided on one side with a plurality of longitudinally spaced apertures; a plurality of double sockets, one for each aperture, said sockets being positioned exteriorly of the arm and each oppositely facing laterally on opposite sides of the arm, a tubular connection for securing each socket to its associated aperture, and an electric lead in said arm and extending through each of said tubular connections for supplying the associated sockets.

50 4. In a chandelier of the type disclosed, the combination of a hollow arm, a shell depending from the arm and provided at opposite ends with means forming a socket, a hollow connecting member for securing each shell to the arm and electric leads extending through said arm and through the hollow connecting means to both socket ends of the shell.

5. In a device of the class described, the combination of a hollow arm, a plurality of electric sockets positioned exteriorly of said arm, reduced neck connecting nipples between the arm and sockets and electric leads in said arm and extending through said nipples to the sockets.

6. In a device of the class described, the combination with a support of a hollow arm secured thereto, a plurality of electric sockets positioned exteriorly of said arm, reduced neck connecting nipples between the arm and sockets and electric leads in said arm and extending through said nipples to the sockets, said arm including a removable cover plate permitting access to the nipples and to the electric leads in the arm and nipples.

7. In a device of the class described, the combination of a depending support, a foot bracket at the lower end of said support, a demountable unit secured to the foot bracket and including a box-like hollow arm extending from said bracket, one side of said arm provided with a plurality of electric sockets and said arm provided at its end remote from the bracket with a control switch, and an electric conductor leading from said foot bracket through said hollow arm to the sockets and switch.

8. A chandelier for supplying electric current to a plurality of heaters in the process of hair waving, comprising a depending support, a foot bracket provided with means for supporting a socket supporting arm, a hollow arm demountably secured at one end to said means and adapted to contain electric conductors, a plurality of electric sockets carried by said arm positioned exteriorly of the arm and adapted to be connected electrically to the conductors in the hollow arm.

9. In a chandelier of the type described, the combination with a depending support, a foot bracket at the lower end thereof, a box-like hollow arm extending from said bracket, electric sockets depending from and spaced below said arm, conductors in the support and in the hollow arm and leading therefrom to the sockets therebelow and said arm having means providing access to the conductors contained therein.

10. An article of manufacture constituting one of a series of separable arms on a chandelier, provided with means for securing the same in place on the chandelier, said arm provided along one side with a plurality of openings, a plurality of complete electric sockets, one for each opening and positioned exteriorly of the same, means for securing each socket to the arm at its associated opening and conductors in the arm having branches extending through the opening and connected electrically to the sockets.

11. A chandelier for supplying electric current to a plurality of heaters in the process of hair waving, comprising a depending support, a foot bracket provided with means for supporting a socket carrying arm, a hollow tubular member constituting a socket carrying arm demountably secured at one end to said means and adapted to contain electric conductors, a plurality of removable

- electric sockets each complete in itself, spaced apart longitudinally along said arm and adapted to be connected electrically to the conductors in the arm.
12. In a chandelier of the type disclosed, the combination of a central support, a plurality of arms extending radially therefrom, each arm provided with a plurality of electric sockets and each arm provided at its outer end with a control switch for the sockets carried by its arm and an electric lead extending from said support, through each of said arms to its associated switch and sockets.
13. In a chandelier of the type disclosed, the combination of a central support, a plurality of arms extending radially therefrom, each arm provided with a plurality of electric sockets and each arm provided at its outer end with a control switch for the sockets carried by its arm, an electric lead extending from said support, through each of said arms to its associated switch and sockets and a plurality of pilot lights, one for each arm carried by its associated arm and operatively connected with the switch to indicate the status of the same.
14. In a chandelier of the type disclosed, a hollow arm provided at one end with a fastening flange for securing the same in place, the other end enlarged to form a housing, a switch in said housing, a plurality of sockets carried by the arm and an electric lead extending through the arm and electrically connecting the switch and sockets.
15. In a chandelier of the type disclosed, a hollow arm provided at one end with means for securing the same in place, the other end provided with a switch and with a pilot light, a plurality of sockets carried by the arm and an electric lead extending through the arm and electrically connecting the switch, pilot light and sockets.
16. In a chandelier of the type disclosed, the combination with a support, of an arm secured at one end of the support and provided at its outer end with a pilot light, means carried by the arm for supplying a plurality of electric hair heaters and means for connecting said light in circuit with the heaters whereby the luminous light will indicate visually that the heaters attached to that particular arm are active.
17. In a chandelier of the type disclosed, the combination of a support, an arm secured at one end to the support and provided at its outer end with a control switch and a pilot light, and provided intermediate its ends with a circuit forming means for supplying electric current to a plurality of electric heaters, said means including said control switch and said pilot light.
18. In a device of the class described, the combination with a support of a hollow arm provided with means at the inner end for mounting the same in place secured to the support, a plurality of sockets depending from said arm and adapted to receive connections with electric heaters, the outer end of said arm being enlarged, a pilot light mounted on top of said enlarged end, a control switch depending from said enlarged end and electric leads positioned in said arm and electrically connecting said sockets, switch and pilot light.
19. In a device of the class described, the combination of a replaceable chandelier arm, means for mounting the same in position, means carried by the arm forming an electric circuit, said means including an electric outlet adapted to supply current to a hair heater, and also including a pilot light and a switch for controlling said circuit.

Signed at New York city in the county of New York and State of New York this 10th day of October, A. D. 1924.

ERNEST UNGER.
